UNITED STATES PATENT OFFICE.

MENDEL PIANKO, OF CHICAGO, ILLINOIS.

CURTAIN-WINDOW.

1,253,525.

Specification of Letters Patent. Patented Jan. 15, 1918.

Application filed May 9, 1917. Serial No. 153,782.

To all whom it may concern:

Be it known that I, MENDEL PIANKO, a citizen of the United States, residing at Chicago, in the county of Cook and State of Illinois, have invented certain new and useful Improvements in Curtain-Windows, of which the following is a specification.

This invention relates to an improvement in curtain lights or windows, and particularly of the type designed for use in providing transparent sections in curtains or similar protectors for automobiles or other vehicles.

In vehicle curtains it is important that some transparent sections be provided, to furnish light to the interior and permit vision therethrough. It has been, and is now customary to make such transparent sections, which will be hereinafter termed lights, of celluloid, stitched or otherwise secured to the curtain to close appropriate openings therein. As practically all such curtains are designed to be rolled or folded when not in use, the lights of the present type have proven objectionable, in that such material, when used in the present manner, soon deteriorates and cracks or breaks, resulting in an unsightly appearance and requiring the additional expense of renewal. Such lights as are now used, in order to permit a rolling or folding without breakage at once, are made of celluloid of comparative thickness and treated with oil, usually castor oil. This oil has the effect to prevent breaking for a short period, but in the end tends to the very effect sought to be avoided. The oil, not only tends to discolor the material and thereby interfere with its transparency, but will freeze under cold weather, and thereby aid in the cracking or breaking of the light. Furthermore, the necessarily comparative thickness of the lights, to further assist resistance to cracking or breaking, as was thought, also tends to this very result, as in bending, one surface of the light must necessarily stretch farther than the other, in direct proportion to the thickness, hence cracking or breaking the light. Therefore, the oil-treated, comparatively thick lights of celluloid have proven very objectionable for vehicle curtains or the like, and have been a constant source of annoyance and expense.

The present invention aims to overcome all the noted objections, and in addition thereto to produce a superior article, both as

to transparency and practically continuous use without breaking or cracking.

The lights of the present invention, in the broad and general scope of their manufacture, are to be constructed of two or more very thin sheets of celluloid, using a material which has not been oil treated. The thin sheets effectively reinforce each other, when bending, and by the comparatively slight difference in the stretching distance of the opposite sides of each sheet in bending, there is little or no tendency to break or crack.

In a more specific form the invention contemplates the use of a thin layer or sheet of gelatin, clear and transparent, between, and preferably uniting, the sheets of celluloid. The gelatin permits the necessary flexibility and yielding of the sheets independently to avoid breaking, while yet uniting the sheets into what may be considered a unitary structure.

The invention will be described in the following specification, reference being had there to the accompanying drawings, in which:—

Figure 1 is a broken elevation, showing a curtain with the improved light in place.

Fig. 2 is a sectional view of the same, the independent sections of the celluloid being particularly illustrated.

Fig. 3 is a sectional view of a modified form of light, wherein gelatin is used between the sheets of celluloid.

The curtain, indicated at 1, represents any type of vehicle protecting section, which is designed to be rolled or folded when desired. The lights, of which there may be any number, and which may be of any size or shape, are transparent sections 2, of a material which will permit such rolling or folding, with such sections secured by marginal stitching 3, to the curtain material, to close an opening therein.

Heretofore such lights have been made of celluloid, as this material more nearly possesses the desired characteristics. The present invention contemplates the use of the same material, but in very thin sheets, and the use of two or more such sheets, 4 and 5, for each light, the sheets, in this adaptation of the invention, being unconnected with each other, except through the means whereby the light as a whole is secured in place in or on the curtain. The thin sheets provide a light having certain highly desired char-

acteristics not possessed by the usual single, comparatively thick strip ordinarily employed. In the first place the thick section, by reason of the unequal stretching of the 5 respective surfaces, will, in bending, as through wind pressure, or rolling of the curtain, tend to a cracking or breaking, and experience has proven such lights to have a very short life. Furthermore, recognizing 10 this objection, the manufacturers have sought a remedy in treating the celluloid with oil, to lessen this tendency. The oil gradually darkens and renders the celluloid materially less transparent, and such oil will freeze in 15 cold weather, and therefore increase the tendency of the light to crack or break. The thin sheets do not require oil treatment, hence their transparency is practically uniformly permanent, and the thin nature of 20 the sheets results in practically a uniform stretching of both surfaces of each sheet in bending with materially less liability to crack or break from this cause. Again the sheets reinforce each other in bending to prevent 25 undue movement of one over the other, and thus life is added to the light. In an emergency, the breaking of one sheet, will not interfere with the usual protection of the light, as such broken sheet may be trimmed 30 away, leaving a single sheet capable for a time of all necessary functions.

As an important and essential feature of 35 the present invention, and to materially strengthen the necessarily thin sheets of celluloid, the use of a section of clear transparent gelatin 6 between such sheets of celluloid is contemplated. The gelatin, as it is perfectly flexible without breaking will 40 materially strengthen the celluloid sheet contraction and act as a reinforce against the

breaking or cracking of such celluloid sheets under even unusual strain. The gelatin is not affected by temperature changes or conditions, and as it is protected against moisture or water, its soluble agent, by the overlying sheets of celluloid, such gelatin will remain intact, and with the celluloid sheets will form a window or light that will not crack or break and will remain permanently transparent. 45

Furthermore, the invention contemplates where excessive strength of the light is desired, the placing of a netting sheet or strip between the celluloid sheets, and while perfect transparency would be somewhat impaired by this construction, still vision may be readily had from within the vehicle, owing to the increased light outside, and the window is practically indestructible. It is not deemed necessary to illustrate this particular form herein. 50 55 60

What is claimed, is:—

1. A curtain light made of a plurality of thin sheets of celluloid united by the means for securing the light to the curtain and 65 otherwise free of connection.

2. A curtain light made of a plurality of thin sheets of celluloid united by the means for securing the light to the curtain and otherwise free of connection, and an inter- 70 posed sheet of gelatin.

3. A flexible light made up of a plurality of thin transparent flexible sections secured together and to the curtains adjacent their edges, the sections being permitted independent yielding throughout their transparent area. 75

In testimony whereof, I affix my signature.

MENDEL PIANKO.
